UNITED STATES PATENT OFFICE.

WILLIAM E. YOULE, OF LOS ANGELES, CALIFORNIA, ASSIGNOR OF ONE-HALF TO J. F. HOLBROOK, OF LOS ANGELES, CALIFORNIA.

CASING-SPEAR.

1,377,301.

Specification of Letters Patent. Patented May 10, 1921.

Application filed September 27, 1919. Serial No. 326,952.

To all whom it may concern:

Be it known that I, WILLIAM E. YOULE, a citizen of the United States, residing at Los Angeles, county of Los Angeles, State 5 of California, have invented a new and useful Casing-Spear, of which the following is a specification.

This invention relates to casing spears of the class commonly used in connection with 10 deep wells for the purpose of removing casing from a well or for loosening it and permitting it to be shifted.

The object of the invention is to provide a casing-spear which engages approximately 15 the entire inner periphery of the casing within the length of the slips or casing engaging jaws and so designed and constructed that said slips may be made of any desired length without weakening the shank 20 of the spear.

Another object is to provide a casing-spear having slips which are guided at their opposed ends and are retained against lateral displacement after being assembled 25 with the spear shank, there being means associated with the shank and capable of removal for permitting a disassembling of the slips from the shank.

A further object is to provide tension 30 means for normalizing the slips, releasable during a casing gripping operation of the slips for subsequent functioning when the slips disengage the casing.

With these and incidental objects in view 35 the invention consists of certain novel features of construction and combination of parts, the essential elements of which are set forth in the appended claims and a preferred form of embodiment of which is hereinafter described with reference to the drawings which accompany and form part 40 of this disclosure.

In the drawings:

Figure 1 is an elevation of my improved 45 casing-spear shown within a well casing, with the parts in the position they occupy when the spear is being lowered to position within the well.

Fig. 2 is an enlarged section on line x^2-x^2 50 of Fig. 1.

Fig. 3 is a section similar to Fig. 2 showing the spear in casing gripping position with the slip elevator released for subsequent slip normalizing operation.

Fig. 4 is a section similar to Fig. 2 show-

ing the slips released from engagement with the casing and normalized by the slip elevator.

Fig. 5 is a transverse section on line x^5-x^5 60 of Fig. 2.

Fig. 6 is a transverse section on line x^6-x^6 of Fig. 2.

Fig. 7 is a transverse section on line x^7-x^7 of Fig. 2.

Fig. 8 is a transverse section on line x^8-x^8 65 of Fig. 2.

Fig. 9 is a detail perspective front view of one of the slips, and

Fig. 10 is a detailed perspective rear view of one of the slips. 70

A well casing being packed in the well by an encircling packing device is held firmly therein, and in order to remove it when the usual types of packers are used, it is necessary to jar on the casing until the 75 packer is broken or torn loose before the casing can be moved. A casing-spear suitable for this purpose must have great strength relative to its size and the shank thereof must be of as large a diameter as possible and free from weakening slots or orifices. Also, as the applied powers at times amounts to several tons, the slips or gripping jaws should engage a relatively 80 large area of the casing, especially in some instances where the casing is old and weakened, as in such instances the casing would be ruptured by a more localized slip engagement.

The casing-spear herein illustrated and 90 described is designed to provide a maximum area of casing engaging slip area and a solid shank, the slips being retained in position and guided in slots formed in annular flanges projecting beyond the body portion 95 of the shank.

Referring to the drawings, A designates a well casing, and B designates the casing-spear which is attached to the end of a string of tools in the usual manner. 100

The shank 1 of the spear is provided with two relatively spaced annular flanges 2-3, the intermediate portion 4 being square, in cross section, and formed to provide a plurality of series of inclined cam surfaces 5, one series on each of the four sides of the shank. The upper flange 2 is provided with radial slots 6 each circumferentially positioned centrally, relative to the companion cam surfaces of the shank with key-ways 105 110

7-7 cut in the opposed side walls of each slot. The lower flange 3 is provided with annular radial slots 9 relatively aligned with the slots 6 of the upper flange 2 and with 5 similar key-ways 10-10 cut in their opposed side walls. The keyways of each relatively aligned pair of slots 6 and 9 and the companion series of cam surfaces of the shank are all correspondingly angularly disposed.

10 Coöperating with the shank are four toothed slips or gripping jaws 12 having outer convex toothed surfaces approximately corresponding in contour to the inner periphery of the well casing and circumferentially extended to form a substantially complete circle. The inner surface of each slip is formed with a series of inclined cam surfaces 13 correspondingly angularly disposed relative to the coöperating series 15 of companion cam surfaces 5 of the shank and the opposed terminal ends of each slip are formed to provide relatively aligned guide tongues 14-15 adapted to engage into the respective guide slots 6 and 9 of the 20 flanges 2-3 of the shank. Projecting laterally from the tongues 14-15 I provide keys 16-16 and 17-17 engaging respectively with the key-ways 7-7 and 10-10 of the flanges 2 and 3.

30 Adjacent the lower tongue 15, the body portion of each slip is formed to provide abutment surfaces 18-18 which are positioned to engage the upper surface of the shank flange 3 to limit the downward movement of the slip. The upper end of the body portion of each slip is provided with similar abutment surfaces 19-19 which are adapted to engage abutment bolts 20, screw-threaded into the upper flange 2, to limit 35 the upward movement of the slips.

40 This construction provides a plurality of slips having a maximum area of casing engaging toothed surfaces and which can be extended to any desired length without any reduction in the cross sectional area of any portion of the main shank of the spear. The slips are accurately guided at their 45 terminal ends and are retained against lateral displacement by the intermeshing 50 keys and keyways, with the movements of the slips limited in both directions by coacting abutments.

55 Slidable on the lower portion 25 of the shank is an annular collar 26 of a diameter sufficient to engage the lower ends of all of the slips and serving as a slip elevator for normalizing the slips preparatory to a withdrawal of the spear from the casing.

60 A nut 27 is screw-threaded on the lower end of the shank and a transverse pin 28 prevents an accidental displacement thereof. Resting on the nut 27 is a collar 29 and a spring 30 is interposed between said collar and the collar or elevator 26. The collar 29 has an annular groove 31 formed in

its under surface and adapted to be engaged, when the spring 30 is compressed, by a latch 32 having a hook nose 33 and adjustably mounted on the elevator 26. The latch 32 is formed of spring metal and has a tension normally tending to maintain the latch in disengaged position.

65 It will be noted that the slips could be moved farther upward, from the normal position shown in Fig. 4, if it were not for 75 the fact that the abutment bolts 20 prevented such additional movement. This extra movement is provided for a disassembling of the slips from the shank, which is accomplished in the following manner.

70 The slips are allowed to drop until the abutment surfaces 18-18 rest upon the upper surface of the flange 3 and the bolts 20 are removed from the flange 2. The slips can then be raised until the abutment surfaces 19-19 contact the under surface of the flange 2 at which time the keys 16-16 and 17-17 of the slips are entirely disengaged from their companion key-ways permitting the slips to be laterally removed 80 from the shank. The slips are assembled on the shank in a converse manner.

75 The operation of the spear will now be described, assuming that the slips are properly assembled on the shank and beginning 95 with the preparatory setting of the slip elevator. In setting the slip elevator, the collar 26 is pushed downwardly, by suitable means, to compress the spring 30 until the nose 33 of the spring latch 32 is in a position to be engaged with the groove 31 of the collar 29. The latch will then be pressed 100 inwardly into engagement with said groove to hold the elevator 26 in lowered position with the spring 30 maintained under tension. The spear is now ready to be lowered 105 into the well casing. As the spear is lowered, the slips being freely movable on their inclined seats, readily accommodate 110 themselves to any inequalities in the diameter of the casing. (See Fig. 1.)

115 When the spear has been lowered to a position where it is desired to engage the casing, the operator causes an upward pull to be exerted on the string of tools, and by such upward pull the spear shank will be elevated relative to the slips, the inclined cam surfaces of the shank acting upon the companion cam surfaces of the slips, to force the slips to casing engaging position, 120 as shown in Fig. 2. The operator now jars upwardly on the tools, and in such upward jarring causes the teeth of the slips to embed 125 in the walls of the casing. This upward jarring also brings the slip elevator into engagement with the lower ends of the slips, by which further movement of said elevator is prevented, and then continues the upward movement of the shank to cause a release of the spring latch of the elevator. 130

The slips being now in firm engagement with the well casing, (see Fig. 3) further lifting or jarring of the spear will loosen or move the casing.

- 5 When the casing has been properly loosened or sufficiently raised in the well, and it is desired to disengage and withdraw the spear therefrom, the operator jars down on the tool string. The effect of this will be to
 10 relieve the slips of the transverse pressure caused by the cam action of the shank cam surfaces on the cam surfaces of the slips, the elevator, by the stored energy of its spring, supporting the slips while the shank
 15 continues its downward movement. This downward movement of the shank will continue until the slips are freed from engagement with the well casing and restored to normal position with the upper abutment
 20 surfaces thereof in engagement with the abutment bolts of the upper flange, (see Fig. 4) after which the spear may be freely withdrawn from the casing.

While the form of device herein shown and described is well adapted to fulfil the objects primarily stated, it is to be understood that it is not intended to confine the invention to the specific form of embodiment herein disclosed, for it is susceptible of embodiment in various forms, all coming within the scope of the claims which follow.

I claim:

1. A casing spear having a solid imperforate shank provided with a plurality of longitudinally disposed series of inclined cam surfaces, and a plurality of one piece toothed slips freely slideable on the shank, each slip having a series of inclined cam surfaces engaging one of the series of cam surfaces of the shank and each of the cam surfaces of the shank and of the slips being devoid of projections or recesses.

2. A casing spear having a solid imperforate shank provided with a plurality of longitudinally disposed series of inclined cam surfaces, and a plurality of one piece toothed slips freely slideable on the shank, each slip having a series of inclined cam surfaces engaging one of the series of cam surfaces of the shank and abutment surfaces coöperating with the shank to limit the movements of the slips, and each of the cam surfaces of the shank and of the slips being devoid of projections or recesses.

3. A casing-spear having a shank provided with a plurality of series of inclined cam surfaces and relatively alined guide slots, and a plurality of toothed slips each having a series of inclined cam surfaces for coöperation with the companion series of cam surfaces of the shank and opposed tongues coöperating with the alined guide slots.

65 4. A casing-spear having a shank pro-

vided with relatively spaced annular flanges having relatively alined guide slots and a plurality of series of intermediate inclined cam surfaces, and a plurality of toothed slips each having a series of inclined cam surfaces for coöperation with the companion series of cam surfaces of the shank and opposed tongues coöperating with the alined guide slots.

5. A casing-spear having a shank provided with relatively spaced annular flanges having relatively alined guide slots and a plurality of series of intermediate inclined cam surfaces, and a plurality of toothed slips each having a series of inclined surfaces for coöperation with the companion series of cam surfaces of the shank and opposed tongues coöperating with the alined guide slots, said slips also having abutment surfaces coöperating with the shank to limit the movements of the slips.

6. A casing-spear having a shank provided with a plurality of series of inclined cam surfaces and relatively alined guide slots with key-ways cut in the walls of the slots, and a plurality of toothed slips each having a series of inclined cam surfaces for coöperation with the companion series of cam surfaces of the shank and opposed tongues coöperating with the guide slots, each tongue having a key coöperating with the companion key-way.

7. A casing-spear having a shank provided with a plurality of series of inclined cam surfaces and relatively alined guide slots with key-ways cut in the walls of the slots, a plurality of toothed slips each having a series of inclined cam surfaces for coöperation with the companion series of cam surfaces of the shank and opposed tongues coöperating with the guide slots, each tongue having a key coöperating with the companion key-way, and removable means preventing disengagement of the keys from the key-ways.

8. A casing-spear having a shank provided with relatively spaced radially slotted annular flanges and a plurality of series of intermediate inclined cam surfaces, with key-ways cut in the walls of the slots, and a plurality of toothed slips each having a series of inclined cam surfaces for coöperation with the companion series of cam surfaces of the shank and opposed tongues coöperating with the guide slots, the slips being formed with movement limiting abutment surfaces adapted to engage the shank flanges and the tongues having keys coöperating with the key-ways, with the keys of the upper tongues spaced from the adjacent abutment surfaces to permit a lateral movement of the slips.

9. A casing-spear having a shank provided with relatively spaced radially slotted annular flanges and a plurality of series of

intermediate inclined cam surfaces, with key-ways cut in the walls of the slots, a plurality of toothed slips each having a series of inclined cam surfaces for co-operation with the companion series of cam surfaces of the shank and opposed tongues 70 slidable in the guide slots, the slips being formed with movement limiting abutment surfaces and the tongues having keys co-operating with the key-ways, with the key of the upper tongues spaced from the adjacent abutment surfaces to permit a lateral movement of the slips, and removable abutment elements associated with the upper 75 flange and preventing disengagement of the keys from the slots.

10. A casing-spear having a square solid imperforate shank with each side formed to provide a series of inclined plane cam surfaces, and four one piece toothed slips freely 80 slidable on the shank and each having a series of inclined plane cam surfaces and slidably retained upon the shank with their cam surfaces co-operating with the companion series of cam surfaces of the shank.

11. A casing-spear combining a shank having a squared portion with each side formed to provide a series of inclined cam surfaces, four toothed slips each having a 85 series of inclined cam surfaces and slidably retained upon the shank with their cam surfaces co-operating with the companion cam surfaces of the shank, a slip elevator slidable on the shank below the slips, a 90 spring for said elevator, and means normally maintaining said spring under tension and releasable by an upward movement of the shank relative to the elevator.

12. A casing-spear having a shank provided with a plurality of series of inclined cam surfaces, a plurality of toothed slips each having a series of inclined cam surfaces for co-operation with the companion series of cam surfaces of the shank, a slip 95 elevator slidable on the shank below the slips, a spring for said elevator, and means normally maintaining said spring under tension and releasable by an upward movement of the shank relative to the elevator.

13. A casing-spear having a shank provided with a plurality of series of inclined cam surfaces, a plurality of toothed slips each having a series of inclined cam surfaces for co-operation with the companion 100 series of cam surfaces of the shank and abutment surfaces co-operating with the shank to limit the movement of the slip, a slip elevator slidable on the shank below the slips, a spring for said elevator, and means normally maintaining said spring under tension and releasable by an upward movement of the shank relative to the elevator.

14. A casing-spear having a shank provided with a plurality of series of inclined 105

cam surfaces and relatively alined guide slots, a plurality of toothed slips each having a series of inclined cam surfaces for co-operation with the companion series of cam surfaces of the shank and opposed tongues 70 co-operating with the alined guide slots, a slip elevator slidable on the shank below the slips, a spring for said elevator, and means normally maintaining said spring under tension and releasable by an upward 75 movement of the shank relative to the elevator.

15. A casing-spear having a shank provided with relatively spaced annular flanges having relatively alined guide slots and a 80 plurality of series of intermediate inclined cam surfaces, a plurality of toothed slips each having a series of inclined cam surfaces for co-operation with the companion series of cam surfaces of the shank and 85 opposed tongues co-operating with the alined guide slots, a slip elevator slidable on the shank below the slips, a spring for said elevator, and means normally maintaining said spring under tension and releasable by 90 an upward movement of the shank relative to the elevator.

16. A casing-spear having a shank provided with relatively spaced annular flanges having relatively alined guide slots and a 95 plurality of series of intermediate, inclined cam surfaces, a plurality of toothed slips each having a series of inclined surfaces for co-operation with the companion series of cam surfaces of the shank and opposed 100 tongues co-operating with the alined guide slots, said slips also having abutment surfaces co-operating with the shank to limit the movements of the slips, a slip elevator 105 slidable on the shank below the slips, a spring for said elevator, and means normally maintaining said spring under tension and releasable by an upward movement of the shank relative to the elevator.

17. A casing-spear having a shank provided with a plurality of series of inclined cam surfaces and relatively alined guide 110 slots with key-ways cut in the walls of the slots, a plurality of toothed slips each having a series of inclined cam surfaces for co-operation with the companion series of cam surfaces of the shank and opposed tongues co-operating with the guide slots, each tongue having a key co-operating with the companion key-way, a slip elevator slidable 115 on the shank below the slips, a spring for said elevator, and means normally maintaining said spring under tension and releasable by an upward movement of the shank relative to the elevator.

18. A casing-spear having a shank provided with a plurality of series of inclined cam surfaces and relatively alined guide 120 slots with key-ways cut in the walls of the slots, a plurality of toothed slips each hav- 125

ing a series of inclined cam surfaces for co-operation with the companion series of cam surfaces of the shank and opposed tongues coöperating with the guide slots, each 5 tongue having a key coöperating with the companion key-way, removable means preventing disengagement of the keys from the key-ways, a slip elevator slideable on the shank below the slips, a spring for said elevator, and means normally maintaining said 10 spring under tension and releasable by an upward movement of the shank relative to the elevator.

19. A casing-spear having a shank provided with relatively spaced radially slotted annular flanges and a plurality of series of intermediate inclined cam surfaces, with key-ways cut in the walls of the slots, a plurality of toothed slips each having a 15 series of inclined cam surfaces for co-operation with the companion series of cam surfaces of the shank and opposed tongues coöperating with the guide slots, the slips being formed with movement limiting 20 abutment surfaces adapted to engage the shank flanges and the tongues having keys coöperating with the key-ways, with the keys of the upper tongues spaced from the adjacent abutment surfaces to permit a lateral 25 movement of the slips, a slip elevator slideable on the shank below the slips, a spring for said elevator, and means normally maintaining said spring under tension and releasable by an upward movement of 30 the shank relative to the elevator.

20. A casing-spear having a shank provided with relatively spaced radially slotted annular flanges and a plurality of series of intermediate inclined cam surfaces, with 35 key-ways cut in the walls of the slots, a plurality of toothed slips each having a series of inclined cam surfaces for coöperation with the companion series of cam surfaces of the shank and opposed tongues slideable in the guide slots, the slips being formed with movement limiting abutment surfaces and the tongues having keys coöperating with the key-ways, with the keys of the upper 40 tongues spaced from the adjacent abutment surfaces to permit a lateral movement of the slips, removable abutment elements associated with the upper flange and preventing disengagement of the keys from the slots, a slip elevator slideable on the shank below the 45 slips, a spring for said elevator, and means normally maintaining said spring under ten-

sion and releasable by an upward movement of the shank relative to the elevator.

21. A casing-spear having a shank provided with relatively spaced radially slotted 60 annular flanges, with key-ways cut in the walls of said slots and a plurality of inclined cam surfaces formed on the shank intermediate said flanges, and a plurality of toothed slips slideable on the shank and co-operating with the companion cam surfaces, each slip terminating with relatively alined 65 tongues engaging their companion slots and each tongue having transversely disposed keys engaging their companion key-ways. 70

22. A casing-spear having a shank provided with relatively spaced radially slotted annular flanges with key-ways cut in the walls of said slots and a plurality of inclined cam surfaces formed on the shank 75 intermediate said flanges, a plurality of toothed slips slideable on the shank and co-operating with the companion cam surfaces, each slip terminating with relatively alined 80 tongues engaging their companion slots and each tongue having transversely disposed keys engaging their companion key-ways, a slip elevator slideable on the shank below the slips, a spring for said elevator, and means normally maintaining said spring under tension and releasable by an upward 85 movement of the shank relative to the elevator.

23. A casing spear having a solid imperforate shank provided with a plurality of 90 series of inclined plane cam surfaces, and a plurality of one piece toothed slips freely slideable on the shank and each having a series of inclined plane cam surfaces for co-operation with the companion series of cam 95 surfaces of the shanks, the toothed surfaces of the several slips forming a substantially complete circular casing engaging surface.

24. A casing spear having a shank, and a plurality of independent slips adapted to 100 engage approximately the entire inner circumference of a casing throughout their length, each slip independently coöperating with the shank to be transversely moved thereby to casing engaging position. 105

Signed at Los Angeles, California, this 19th day of September, 1919.
